UNITED STATES PATENT OFFICE.

MORTON D. STICKLE, OF MOORE, PENNSYLVANIA.

SANITARY CIGAR-CUTTER.

1,251,300.

Specification of Letters Patent. Patented Dec. 25, 1917.

Application filed October 9, 1916. Serial No. 124,604.

To all whom it may concern:

Be it known that I, MORTON D. STICKLE, a citizen of the United States, residing at Moore, county of Delaware, and State of Pennsylvania, have invented certain new and useful Improvements in Sanitary Cigar-Cutters, of which the following is a specification.

This invention relates to cigar cutters.

10 Automatic and manually operated cigar cutters, such as are commonly used in cigar and drug stores and at other places, are very insanitary and tend to convey germs due to the fact that it is a common practice to moisten the end of the cigar by first inserting it in the mouth and then severing the tip by introducing it into the cutter. The blades of those cigar cutters heretofore known to the art, repeatedly present the same cutting edge and surface, as the device is successively used by different persons. An insanitary condition consequently results and even though the cigar be presented to the cutter when perfectly dry, its handling 15 is liable to cause transference of germs to the cigar and from it to the cutter. Repeated usings of a cigar cutter cause a certain accumulation of cuttings on the blade. These, and other, circumstances render the 20 usual cigar cutter an insanitary and germ carrying device.

My invention has for its object the provision of an improved cigar cutter wherein a fresh and clean cutting device or means is 25 presented to successive cigars so that an entirely different, un-used, cutting device is presented each time the machine is used. By this means I minimize the danger of insanitary conditions prevailing in my cigar cutter 30 and prevent accumulation of any clippings or foreign matter on the cutter.

A practical embodiment of my invention comprises a plurality of oppositely movable cutters which preferably assume the form of 45 a device arranged in superposed relation to each other and having cutting openings which are adapted to come into register to receive the tip of the cigar and, when actuated, shear off the cigar tip. Each operation 50 of the machine presents fresh cutting portions of the device so that those portions used are not available for use on any subsequent operation of the machine, at least until they have been cleaned or disinfected. The 55 cutting strips or tapes may be dispensed with, after they have run through the ma-

chine and performed their function, and new strips substituted. I provide means whereby each user can set the machine in operation, such means automatically stopping the machine after the cigar tip has been severed. Preferably the cutting tapes or strips wind on drums all of which are simultaneously actuated by spring means acting on one of the drums and gearing connecting 60 the drums in such manner that the tapes or strips will move in opposite directions.

Various modifications may be resorted to in carrying out my invention and I do not, therefore, desire the disclosure hereinafter 70 given and that which is found in the drawings to be considered as restrictive of the invention as the same is merely illustrative thereof.

In the accompanying drawings:

Figure 1 is a plan view;

Fig. 2 a longitudinal section through Fig. 1;

Fig. 3 a horizontal section on line 3—3 of Fig. 4;

Fig. 4 a longitudinal section on line 4—4 of Fig. 1;

Fig. 5 a detail of the detent; and

Figs. 6 and 7 detail plan views of the upper and lower bands, strips or tapes.

The mechanism is contained within a suitable case or shell 1 any part of which may be removable to afford access to the interior thereof. Rising within the case 1 is a hollow shell 2 in the bottom of which is a removable drawer 3 having any suitable handle or pull 4. The drawer 3 catches the severed cigar tips which may be removed by pulling out the drawer and discharging the contents thereof.

At 5, 6, 7, 8 appear four drums which are carried by axles or shafts 9, 10, 11, 12 revolvably mounted in the sides of the casing 1. The drums 5, 6, 7, have gear wheels 13, 14 and 15 respectively. Gears 13 and 14 mesh. 90 A pinion 16 on a stub shaft 17 meshes with the gears 14 and 15 so that said gears rotate in opposite directions at the same speed. The drum 6 is connected to its shaft 10 by a spring 18, whereas the other drums are 100 fast on their shafts. The shaft 10 has a squared portion 19 to which a key may be applied for winding the spring 18.

A steel tape, band, or strip 20, shown in detail in Fig. 7, is suitably connected, in any 110 preferred detachable manner, to the drums 6 and 7 and winds onto the drum 7. A simi-

lar tape, band or strip 21 shown in Fig. 6 is detachably connected to the drums 5 and 8 and winds onto the drum 5. The tapes or strips 20, 21 are adapted to slide over the 5 upper flat face of the top 2^a of the shell 2 and are arranged in superposed relation. The strip or band 20 has equi-distantly spaced circular cutting openings 22. The band 21 has similar openings 23. The openings 23 are adapted to come into register with the openings 22 so that when the cigar tip is introduced through the openings in the superposed strips and the cutter is set in operation, said tip will be severed or sheared off by the opposite movements of the strips 20, 21 and the tip will then fall through the opening 24 in the top 2^a and drop into the drawer or tray 3. The tapes 20, 21 have 10 detent slots 25, 26 which are square at one end 27 and rounded at the other end 28. The squared and rounded ends of the slots 25 are arranged oppositely to those of the slots 26.

Mounted on a rock shaft 29 is a locking 25 detent 30 which has teeth 31, 32 at its respective ends. The teeth 31, 32 are adapted to enter the slots 25, 26 of the respective bands or tapes 20, 21 to arrest them as shown in Fig. 5. On the locking of the 30 detent the tooth 31 first releases the upper tape 21, allowing it to shift, until the point 32 has entered one of the slots 26 and engaged the margin thereof to arrest the upper tape 21. Immediately the tooth 31 is 35 free of the tape 20, that tape moves in the opposite direction until the end of the slot 25 encounters the tooth 32. The tooth 32 enters another of the slots 26 and arrests the tape 21. On the next operation of the 40 machine, the same action occurs so that the tapes 20, 21 are stepped along, in opposite directions, by the action of the spring 18, to shear off the cigar tip. Successive openings 22, 23 being presented for use, each 45 user of the machine has his cigar cut by clean and uncontaminated parts of the bands.

Any suitable means may be provided for locking the shaft 29, one such means comprising a U-shaped member 33 secured to shaft 29 and provided with buttons 34, 35 which are alternately depressed by the users of the machine. Any proper means may be employed for holding the detent in its 55 locked position, one such means comprising a V-shaped spring 36 whose apex steps from one depression to another of the serrated piece 37, Fig. 4.

The gears cause the drums 5 and 7 to positively wind the tapes.

The distance between the teeth 31, 32 is such that when one of these is in locking

engagement with the openings 25, 26, the remaining tooth will be just at the edge of the inner side of the adjacent controlling 65 opening, ready to enter that opening.

When the tapes have wound from one drum onto the other, they may be removed, disinfected and replaced, or, new tapes substituted therefor.

The openings 22 may be of other shape than circular, if desired.

Having thus described my invention what I claim as new, and desire to secure by Letters Patent, is:

1. In a sanitary cigar cutter, superposed oppositely movable cutting tapes adapted to sever a cigar tip, and means for moving said cutting tapes progressively step by step in opposite directions.

2. In a sanitary cigar cutter, superposed oppositely movable perforated cutting tapes adapted to sever a cigar tip, and means for simultaneously moving the tapes progressively, step by step in opposite directions.

3. In a sanitary cigar cutter the combination of oppositely movable cutting devices having cutting openings adapted to pass into and out of register, said cutting devices being movable each across the face of 90 the other, means for moving said cutting devices in opposite directions and detent means co-operating with both of said cutting devices adapted, when operated, to release and again lock them, whereby said cutting 95 devices may have a step by step movement in opposite direction.

4. In a sanitary cigar cutter the combination with tapes or strips having cutting means and adapted to travel progressively, 100 step by step across each other's face, of means for operating said tapes as aforesaid comprising actuating means and means for releasably locking said tapes.

5. In a sanitary cigar cutter the combination with tapes having cutting means and adapted to travel across each other's face, of means for moving said tapes in opposite directions, said tapes having detent locking openings, and a duplex detent whose pallets 110 or teeth are adapted for alternate entry into the detent locking openings.

6. In a sanitary cigar cutter the combination with inter-gear'd drums, of a motor for actuating said drums, superposed tapes 115 or strips running from one drum to another, said drums being adapted to move the tapes or strips in opposite directions, said tapes or strips having cutting means adapted for co-operation, and controlling means for said 120 tapes or strips.

In testimony whereof, I hereunto affix my signature:

MORTON D. STICKLE.
